LATCH MEANS

George E. Dath, Mokena, Ill., assignor to W. H. Miner, Inc., Chicago, Ill., a corporation of Delaware

Application February 3, 1947, Serial No. 726,068

1 Claim. (Cl. 292—207)

1

This invention relates to improvements in latch means, and more particularly to latches for locking the operating lever handles of rotary door fasteners in fixed position.

One object of the invention is to provide simple and efficient latch means for automatically locking the handle lever of a rotary operating bar of a fastener for hinged doors in fixed position when the doors are fastened in closed condition and which may be readily released by gripping the hand grip portion of the handle lever in the operation of forcing the door open.

A more specific object of the invention is to provide a mechanism as set forth in the preceding paragraph, wherein the latch means includes a spring pressed latch bolt carried by the operating handle lever engageable with a fixed keeper to lock the handle lever in position, and wherein the spring pressed bolt is disengageable from the keeper by means on the operating handle lever actuated through pressure exerted by the operator's hand in gripping the hand grip portion of the handle lever.

Other objects of the invention will more clearly appear from the description and claims hereinafter following.

In the drawings forming a part of this specification, Figure 1 is a rear elevational view of the body of an automobile truck having hinged doors provided with a door fastener of the rotary bar type, illustrating my improved latch means in connection therewith. Figure 2 is a broken elevational view, on an enlarged scale, corresponding to Figure 1, showing the structure at the left hand end of the mid portion of the right hand door. Figure 3 is a horizontal sectional view, corresponding substantially to the line 3—3 of Figure 2. Figure 4 is a view, similar to Figure 3, showing the parts in a different position. Figure 5 is a plan view of the operating handle lever of the door fastener illustrated in Figures 1 to 4 inclusive. Figure 6 is a plan view of the sliding latch bolt. Figure 7 is a side elevational view of Figure 6, looking downwardly in said figure. Figure 8 is a plan view of the bolt retracting lever member of the improved latch means. Figure 9 is a view, similar to Figure 2, illustrating another embodiment of the invention. Figure 10 is a horizontal sectional view, corresponding substantially to the line 10—10 of Figure 9. Figure 11 is a horizontal sectional view, on an enlarged scale, corresponding substantially to the line 11—11 of Figure 9, said view being partly broken away. Figure 12 is a side elevational view of the bolt retracting lever of the latch means shown in

2

Figures 9, 10, and 11. Figure 13 is a side elevational view of the latch bolt shown in Figures 9, 10, and 11.

In said drawings, 10 indicates the end wall of an automobile truck, and 11, the door opening of said wall, which is closed by hinged doors 12 and 13 secured by the door fastener 14, which is mounted on the door 12 and is of the well-known rotary bar type, comprising a rotary operating bar 15 having keeper engaging crank members 16—16 at the top and bottom ends cooperating with the usual fixed keepers, and an operating handle lever 17 for rotating the bar. The door 12 is of well-known design and is provided with a pocket 18 in the outer wall thereof into which the handle lever 17 swings.

Referring first to the embodiment of the invention illustrated in Figures 1 to 8 inclusive, my improved latch means comprises broadly a fixed keeper A, a sliding latch bolt B, a lever member C for retracting the latch bolt, and a spring D for projecting the bolt.

In carrying out the invention as illustrated in Figures 1 to 8 inclusive, I provide the operating handle lever, which is of channel-shaped, transverse cross section, with a relatively short, vertically disposed, lengthwise extending wall portion 19 on the outer side at the hand grip portion 20 thereof, which is parallel to the web 21 of the channel-shaped lever. The wall 20, the web 21, and the top and bottom flanges 22 and 23 of the lever 17 together define a guideway 24 of substantially rectangular cross section for the bolt B. The web 21 is provided with an opening 25 therethrough, which is located beyond the inner end of the guideway 24 and is arranged to accommodate the outer end portion of the keeper A when the handle lever is swung to its innermost position, as shown in Figure 3. At the hand grip end 20 of the lever, the web 21, which forms the back wall of the channel-shaped lever, is cut away, or interrupted, as indicated at 26, to accommodate the bolt retracting lever member C.

The keeper A is in the form of an outstanding post on the rear wall 27 of the pocket 18 of the door 12 and has a hooked outer end 28 with which the latch bolt B is engageable.

The latch bolt B is in the form of an elongated sliding block mounted on the guideway 24. The bolt B has a beveled front end portion 29 engageable with the hooked end 28 of the keeper A. At the inner or rear end, the bolt B is reduced in thickness, thereby providing a rearwardly extending stem or shank portion 30 and a shoulder 31 at the point where the stem merges with the

main body portion of the bolt. The face or surface portion of the shoulder 31 is inclined with respect to the longitudinal axis of the bolt, as clearly shown in Figure 3, and forms an abutment for the end of the spring D. At the extremity of the stem or shank 30, the bolt is provided with an inturned lug 32 with which the lever member C cooperates.

The bolt retracting lever member C is in the form of a channel-shaped arm having a lengthwise extending web 33 and top and bottom flanges 34 and 35. The flanges 34 and 35 embrace the top and bottom sides of the hand grip end 20 of the lever 17 and the web 33 terminates short of the inner end of the channel-shaped arm, as shown most clearly in Figures 3 and 4. At the inner end of the web 33, the flanges 34 and 35 of the channel-shaped arm are provided with rearwardly projecting pivoted ears 36, which engage over the top and bottom of a rearwardly projecting pivot lug 37 on the lever 17, the lever member C being pivotally supported on this lug by a pin 38 extending through the ears and the lug. Beyond the pivoted ears 36—36, the flanges 34 and 35 are braced by a vertical connecting end wall 39. The web 33 of the lever member C has an inward enlargement at its inner end, as indicated at 41, and this thickened portion presents an inclined spring abutment face 42 for the spring D opposed to the face of the shoulder 31 of the bolt B. The inward enlargement 41 has a laterally extending lug or finger 43 projecting from the inner side thereof, which engages with the lug 32 of the bolt to retract the latter when the lever is swung inwardly.

The spring D, which comprises a small helical coil, is interposed between the shoulder 31 of the bolt B and the abutment face 42 of the lever member C and is preferably held centered by projecting bosses 44—44 on the shoulder and abutment face which engage within the ends of the spring. The spring D, which reacts between the bolt B and the lever member C, normally holds the bolt projected, as shown in Figure 3.

The operation of my improved latch means, illustrated in Figures 1 to 8 inclusive, is as follows: In actuating the operating lever 17 of the door fastener to force the door closed, the same is swung inwardly toward the door into the pocket 18 to the position shown in Figure 3. As the lever is thus swung inwardly, the hooked end of the keeper A passes through the opening 25 of the lever and is engaged by the latch bolt B, which cams over the outer end of the keeper which is provided with a beveled end face 40 cooperating with the beveled end of the bolt. When the lever reaches the position shown in Figure 3, the spring pressed bolt B snaps into engagement with the hooked portion of the lever to automatically lock the latter in fixed position. To unlock the lever 17, the latch bolt B is disengaged from the keeper by retracting the same through pressure applied to the lever member C, the attendant gripping the hand grip end of the operating lever 17 and, in gripping the same, applying pressure to the lever member C to swing the same toward the lever 17, thereby swinging the lug 43 against the lug 32 of the bolt to slide the latter toward the right, as seen in Figure 3, to the retracted position shown in Figure 4.

Referring next to the embodiment of the invention illustrated in Figures 9 to 13 inclusive, the improved latch means comprises broadly a keeper E, a sliding latch bolt F, a bolt retracting lever member G, and a spring H.

In carrying out the invention, as shown in Figures 9 to 13 inclusive, I provide an operating lever 117 for the door fastener, which lever is of channel-shaped cross section and is the equivalent of the lever 17 hereinbefore described. The lever 117 has an opening 45 similar to the opening 25 of the lever 17 and adapted to provide a passage for the projecting keeper E. The channel-shaped lever 117 has the hand grip portion thereof, which is indicated by 46, provided with rearwardly projecting, lengthwise extending, horizontal, top and bottom flanges 47—47. The flanges 47—47 extend from the outer extremity of the hand grip to the opening 45 and have the inner edges of the portions thereof, immediately adjacent the opening, connected by a vertically disposed, lengthwise extending web 48, which is outwardly offset at the end thereof remote from the opening 45, providing a curved lip 49. The lip 49 forms a stop for the lever member G hereinafter more fully described. The straight portion of the web 48, the top and bottom flanges 47—47, and the vertical web of the hand grip proper, which web is indicated by 50, form a guideway for the inner end portion of the bolt F.

The keeper E is of substantially the same design as the keeper A hereinbefore described, having a hooked end 51 provided with a cam face 52 at the extremity thereof adapted to cooperate with the bolt F.

The bolt F has a head 53 at its outer end of substantially rectangular cross section, adapted to engage with the hooked end of the keeper E, the end face of the head being beveled, as indicated at 54, to cooperate with the cam face 52 of the keeper. Rearwardly extending from the head 53, the bolt is reduced in size, providing a shank portion 55, which is enlarged at its rear end, as indicated at 56. The enlargement 56 has a wedge face 57 on its inner side for a purpose hereinafter pointed out.

The lever member G, which is in the form of an elongated arm or fingerpiece, is swingingly supported between the top and bottom flanges 47—47, being pivotally connected to the hand grip 46 at the end of the latter by a pin 58 extending through the enlargement 59 at the corresponding end of the member G. The enlargement 59 presents a transverse abutment face 60 at its inner side on which the end of the spring H bears. At the opposite end, the arm of the lever member G is provided with a laterally, inwardly extending enlargement or head 61, having a wedge face 62 at its rear side engaging the wedge face 57 of the bolt. The head portion 61 of the lever member G is overhung by the lip 49 of the web 48 of the hand grip portion of the lever 117 and has its movement away from the lever 117 limited thereby. Between the ends thereof, the flanges 47—47 are suitably cut away, as indicated at 63, to render the member G accessible for operation, that is, to be pressed inwardly.

The spring H, is in the form of a helical coil interposed between the inner end of the bolt F and the abutment face 60 of the lever member G and holds the bolt yieldingly projected.

The operation of the improved latch means shown in Figures 9 to 13 inclusive is similar to the operation of the latch means hereinbefore described in connection with Figures 1 to 8 inclusive, with the exception that the bolt F is withdrawn from engagement with the keeper E by camming action between the wedge faces 57

and 62 of the bolt and the swinging lever member G.

I claim:

In a latch means for a swinging operating lever having a hand grip portion at its outer end, the combination with a latch bolt mounted on said lever for sliding movement lengthwise of said lever; of a spring abutment on said bolt between the ends thereof; a laterally projecting lug on said bolt outwardly beyond said spring abutment; an arm pivoted at its outer end on the hand grip portion of the lever for lateral swinging movement toward and away from said hand grip; a laterally inwardly projecting lug on said arm inwardly of the pivot thereof, said lug being engaged with the lug of said bolt to retract the latter when the arm is swung laterally toward said hand grip portion, said arm having a spring abutment face at the base of the lug thereof;

and a spring bearing at opposite ends on said spring abutment of the bolt and abutment face of said arm, and reacting between said bolt and arm to project the former to latching position.

GEORGE E. DATH.
